ASH TRAY

Kenneth R. Richards, Mason City, Wash.

Application June 7, 1939 Serial No. 277,935

7 Claims. (Cl. 131—242)

This invention relates to an ash tray and it is one object of the invention to provide an ash tray including a casing having a receptacle therein and shutters for closing an opening in the top 5 of the casing having actuating means for moving the shutters to closed position when the ash tray is lifted from a support such as a table or the like, or accidentally turned over or knocked from the table. It will thus be seen that if the ash 10 tray is accidentally turned over or knocked from a table, the shutters will be closed and ashes and cigarette stumps prevented from spilling out of the same.

Another object of the invention is to provide an 15 ash tray of the self closing type wherein the means for actuating the shutters includes a disk disposed under the bottom of the casing where it will be moved to open the shutters by engagement with the top of the table when the ash tray is set 20 upon the table.

Another object of the invention is to provide the ash tray with supports for cigars or cigarettes, the supports being disposed at ends of the opening in the casing and so mounted upon the 25 inner receptacle at ends of the upper opening therein that, while they are normally in a raised position for use, they will be swung downwardly into the casing and deposit cigarettes or cigars resting on them into the inner receptacle when 30 the shutters are moving toward closed position.

Another object of the invention is to provide an automatically closing ash tray which is of neat appearance, efficient in operation, and not liable to get out of order.

35 The invention is illustrated in the accompanying drawing, wherein:

Fig. 1 is a perspective view of the improved ash tray.

Fig. 2 is a vertical sectional view taken longitudinally through the ash tray.

Fig. 3 is a sectional view taken transversely through the ash tray on the line 3—3 of Fig. 1.

Fig. 4 is a fragmentary perspective view illustrating the manner in which the supports for 45 cigars and cigarettes are pivotally mounted for swinging movement into and out of position for use.

The casing 1 of this ash tray is formed of sheet 50 metal or other suitable material and is semi-circular when viewed in side elevation. The bottom 2 is flat so that the tray will rest firmly on a table or other support, and upon referring to Fig. 2, it will be seen that the bottom is formed with a center opening 3 surrounded by an upwardly 55 offset abutment ledge or flange 4. At its top, the

casing is formed with an opening 5 through which ashes and stumps of cigarettes and cigars are to be dropped into the inner receptacle 6 disposed within the casing and firmly supported therein by brackets 7 which project from opposite sides of the receptacle and are secured to side walls of the casing by screws 8. The top wall sections 9 of the casing are arcuate longitudinally, as are also the top wall sections 10 of the inner receptacle which are spaced from each other to provide an opening 11 through which the ashes and stumps of cigars and cigarettes drop into the receptacle.

In order to prevent contents of the inner receptacle from spilling out of the ash tray in case 15 the ash tray is accidentally turned over or knocked from the support on which it rests, there have been provided shutters 12 which are arcuate longitudinally and are mounted to operate in the space between the arcuate upper wall sections 9 and 10 of the casing and receptacle. These shutters are carried by arms 13 extending from their side edges and pivotally mounted for swinging movement by screws 14 carried by the side walls of the casing and constituting pivot pins for the 20 arms. The arms of each shutter are connected by a cross rod or bar 15 and these rods pass through the sleeves 16 at upper ends of links 17, the lower ends of which are pivoted to lugs 18 extending upwardly from a disk 19. This disk is 30 of such diameter and thickness that it will fit into the recess defined by the upwardly offset flange 4 with its under face flush with the under face of the bottom 2 of the casing. Therefore, the casing may rest flat on a table and since the disk will be 35 held in its raised or retracted position, the shutters will be held open. Pins 20 which guide movement of the disk into and out of the retracted position within the center seat of the bottom 2, extend upwardly from the disk and are slidably 40 received in sleeves 21 and in order to urge the pins downwardly there have been provided springs 22. The springs are compressed and held under tension when the disk is moved upwardly into its seat, but if the ash tray is turned over, lifted from 45 the table, or accidentally knocked from its support, the springs expand and force the pins 20 and the disk 19 downwardly. As the disk moves downwardly it exerts pull on the links 17 and as these links are drawn downwardly they exert 50 pull on the cross rods 15 to swing the arms 13 about their pivots and move the shutters 12 to closed position. The contents of the inner receptacle will thus be confined in the casing and prevented from spilling out of the same.

When the tray is to be emptied, it is lifted from its support and after being carried to trash box or other place of disposal, it is turned upside down and pressure applied to the disk to force it to its retracted position and move the shutters to open position, permitting the contents of the inner receptacle to pass out through the openings 11 and 5 of the receptacle and casing.

Holders 23 upon which cigarettes and cigars are to be placed are provided at opposite ends of the opening 5 in the top of the casing and these holders are provided with depending shanks 24. The holders are formed of resilient sheet metal so that they will have gripping engagement with cigars or cigarettes placed thereon but the shanks are formed of stiff metal. The shanks are pivotally mounted between bearing brackets 25 by pins 26 and lower portions of the shanks are bent to form arms 27. Springs 28, which are coiled about the pins, have their arms bent to form hooks 29 and 30 for engaging the shanks 24 and adjacent bearing brackets 25. These springs tend to swing the shanks upwardly and maintain the shanks and their arms 27 in position for abutting engagement with ends of the top sections 9 and 10 of the casing and inner receptacle which limit movement of the shanks under influence of the springs and normally maintain the holders 23 in a horizontal position above ends of the opening 5 of the casing. When, however, the shutters are swung toward a closed position, they exert pushing force on the arms 27 and the shanks will be swung about the pins 26 to move the holders into the casing and the upper portion of the receptacle where they will be out of the path in which the shutters move and not interfere with closing of the shutters. When the shutters are returned to open position the springs swing the holders back to elevated position over the casing for use.

Having thus described the invention, what is claimed is:

1. An ash tray comprising a casing having an opening in its top, an inner receptacle mounted in said casing and having an opening in its top under the opening of the casing, shutters operating in space between top walls of the casing and receptacle, arms extending from said shutters between side walls of the casing and receptacle and pivoted in spaced relation to their lower ends, cross rods connecting lower ends of companion arms, links having their upper ends loosely engaged about said cross rods, a disk under the bottom of said casing, lugs extending upwardly from said disk into said casing and pivoted to lower ends of said links, tubes depending from the bottom of said receptacle, pins rising from said disk and slidably engaged in said tubes, and springs in said tubes urging the pins downwardly to move the disk away from the bottom of the casing and exert pull on said links to swing the arms about their pivots and move the shutters into closing relation to the opening of the casing.

2. An ash tray comprising a casing having an arcuate top wall formed with an opening intermediate its length, the bottom of the casing being formed with an opening at its center and about the center opening being offset upwardly to form a seat in the under face of the bottom and an abutment flange surrounding the opening in the bottom, a receptacle mounted in said casing in spaced relation to side walls of the casing and having an arcuate top wall formed with an opening under the opening in the top wall of the casing, arcuate shutters operating in space between top walls of the casing and the receptacle, arms

extending from said shutters between side walls of the casing and receptacle and pivotally mounted in spaced relation to their lower ends with the arms of one shutter extending in crossed relation to arms of the other shutter, a disk fitting into the seat of the bottom of the casing against said flange when in a retracted position and being movable downwardly out of the seat, lugs extending upwardly from said disk and passing through the opening in the bottom of the casing when the disk is in its retracted position, rods connecting companion arms, and links connecting said lugs with said rods for exerting downward pull on the rods and moving the shutters to closed position when the disk moves out of its seat.

3. An ash tray comprising a casing having an opening in its top, a receptacle mounted in said casing and having an opening in its top under the top opening of the casing, shutters for closing the top opening of said casing operating in space between the receptacle and the casing, arms pivotally mounted and carrying said shutters, a disk under the bottom of said casing and movable from a retracted position against the bottom of the casing to a lowered position, and means connecting said disk with said arms for swinging the arms about their pivots and moving the shutters to closed position when the disk moves downwardly away from the bottom of the casing.

4. An ash tray comprising a casing having an opening in its top, a receptacle mounted in said casing and having an opening in its top under the top opening of the casing, closure means for the top opening of the casing having mounting arms pivoted for swinging movement to move the closure means into and out of closed position, and actuating means for said arms normally holding the closure means in closed position and being disposed in position for engaging a support when the casing is set thereon and adapted to be moved by the support for moving the closure means to open position.

5. An ash tray comprising a casing having an opening in its top, a receptacle mounted in said casing and having an opening in its top under the top opening of the casing, closure means for the top opening of the casing movable into and out of closed position, and actuating means disposed in position for engagement with a support when the casing is set thereon and being adapted to move the closure means to open position when the casing is set on the support.

6. An ash tray comprising a casing having an opening in its top, a receptacle mounted in said casing and having an opening in its top under the top opening of the casing, shutters for closing the top opening of said casing operating in space between the receptacle and casing, means for moving said shutters into and out of closed position including an operating member disposed in position for engagement with a support for moving the shutters to open position when the casing is set upon the support, and holders movably carried by said receptacle and normally projecting upwardly through the top opening of the casing, said holders having portions extending in the path of movement of the shutters for engagement thereby to move the holders downwardly into retracted position through the top openings of the casing and receptacle when the shutters are moved to closed position.

7. An ash tray comprising a casing having an opening in its top, a receptacle mounted in said casing and having a top opening under the top

opening of said casing, shutters for closing the top opening of said casing movable through space between tops of the receptacle and the casing into and out of position to close the top opening of said casing, means for moving said shutters into and out of closed position including an operating member disposed in position for engagement with a support for moving the shutters to open position when the casing is set upon the support, bearing brackets carried by said receptacle at ends of the top opening thereof, holders, shanks for said holders pivoted to said brackets and having their lower portions bent to form reversely extending

abutment arms, and springs for swinging the shanks upwardly and disposing said holders above ends of the opening of the casing in position for use, upward movement of the holders being limited by engagement of the shanks and their arms with top walls of the casing and the receptacle at ends of their top openings, and said shutters when moved to closed position having engagement with the arms and shanks to swing the holders downwardly through the top openings to 10 retracted position under the shutters. 5
